(57) **CLAIM**

The ornamental design for a spray head, as shown and described.

DESCRIPTION

FIG. 1 is a front perspective view of the spray head showing our new design;

FIG. 2 is a front elevational view thereof;

FIG. 3 is a side elevational view, the other side being a mirror image thereof;

FIG. 4 is a back elevational view thereof;

FIG. 5 is an overhead plan view thereof;

FIG. 6 is a bottom plan view thereof; and,

FIG. 7 is a front perspective view wherein the spray head is shown in context with a can, which is shown in broken lines and forms no part of the claimed design.
